C. A. WICKSTROM

REEL

Filed March 26, 1925

Inventor
Charles A. Wickstrom

UNITED STATES PATENT OFFICE.

CHARLES ALBIN WICKSTROM, OF WESTERN SPRINGS, ILLINOIS, ASSIGNOR TO WESTERN ELECTRIC COMPANY, INCORPORATED, OF NEW YORK, N. Y., A CORPORATION OF NEW YORK.

REEL.

Application filed March 26, 1925. Serial No. 18,406.

This invention relates to reels, and more particularly to reels for coiling cables and other heavy materials.

The object of this invention is to provide a reel which is simple and rigid in construction, may be economically manufactured, and is particularly efficient for holding cables and other heavy materials.

One form of the invention is embodied in a reel comprising a pair of heads fastened at each end of a tubular drum. The heads are provided with central apertures adapted to receive suitable hub members which are interconnected by means of a plurality of connecting rods or bolts. These bolts also serve to properly position the hub members and to fasten them to the heads. The number and arrangement of the bolts are such that they serve to guide a shaft or arbor, inserted through one of the hub members, to facilitate its passage through the opposite hub member.

One embodiment of the invention is illustrated in the accompanying drawings, in which

Fig. 1 is an end view of a reel embodying the features of the present invention;

Fig. 2 is an axial section taken on the line 2—2 of Fig. 1, and

Fig. 3 is an enlarged fragmentary detail view of a portion of the structure shown in Fig. 2.

Referring to the drawings in detail, a tubular drum 10, preferably composed of sheet metal, is suitably fastened between two steel heads 11 as by means of a plurality of bolts 12 which protrude through the heads and are threaded at each end to receive a nut 13. The drum 10 encircles a pair of metal rings 14 fastened on the inner side of the heads 11 and is thereby accurately centered with respect to the heads. Each of the heads 11 may be provided with a peripheral flange 16 to increase its resistance against becoming indented or distorted while being rolled or conveyed from one place to another. A metal ring 17 may be fastened to the inner side of the flanges 16 to further add to the strength of the heads and thereby lengthen the life of the reels.

Each head 11 is provided with a central circular aperture 20 within which is received a hub member 21. The hub members 21 are each provided with a central bore 22 and an

internal annular flange 23. The outer face 55 of the flange 23 rests against and is rigidly fastened to the inner face of the head 11, as will hereinafter be described.

The hub members 21 are interconnected by a plurality of rods 25 which are provided at each end with reduced portions 26 forming shoulders 27 against which the hub members 21 are secured and thereby properly positioned. The reduced ends 26 of the rods 25 protrude through suitable apertures provided therefor in the hub members 21 and heads 11 and are threaded to receive nuts 29, which when tightened cooperate with the shoulders 27 to rigidly interconnect the hub members 21 and firmly fasten them to the heads 11.

The hub members 21 are counterbored or beveled at their inner ends as indicated at 30, to facilitate the insertion of a shaft or arbor (not shown) and the number and arrangement of the rods 25 is such that a shaft inserted through one of the hub members is guided by either pair of adjacent rods to the bore of the opposite hub member. This guiding is further facilitated since the rods 80 25 are arranged so that they extend slightly over the edge of the beveled portion and that the clearance between adjacent rods is less than the diameter of the opening 20.

One of the heads 11 is provided with a slot 35 which is located immediately above the surface of the drum 10 and serves as a means for holding the forward end of the cable or other material being coiled. A plurality of apertures 36 provided near the peripheries of each of the heads 11 serve as a means for tying the outer end of the coiled material to the reel.

Although there is herein shown and described one specific embodiment of the invention, it should be understood that the invention is capable of other applications and should be limited only by the general scope of the appended claims.

What is claimed is:

1. A reel comprising a pair of heads having apertures therein, and a plurality of members interconnecting the heads located adjacent to the apertures and relatively spaced by a distance less than the distances 105 across the apertures.

2. A reel comprising a pair of heads, a hub member for each head having an aper-

ture therethrough terminating in an enlarged opening on the internal face of the hub member, and a plurality of members interconnecting the hubs spaced apart by a distance less than the distances across the apertures and positioned with portions thereof extending within the boundaries of the enlarged openings.

3. A reel comprising a pair of heads having apertures therein through which a sup-

porting shaft extends, and a plurality of members interconnecting said heads and spaced to confine the shaft in passing between the heads within the inner boundaries established by said members.

In witness whereof, I hereunto subscribe my name this 13th day of March, A. D., 1925.

CHARLES ALBIN WICKSTROM.
